SURGICAL FRAME FOR HOSPITAL BEDS

Earl E. Longfellow, Warsaw, Ind., assignor to
Harry H. Leiter, Warsaw, Ind.

Application July 2, 1938, Serial No. 217,232

1 Claim. (Cl. 5—92)

My invention relates to surgical frames for hospital beds, and more particularly to such frames which are adjustable and embody improved and simplified construction.

It is an object of my invention to provide a new and improved surgical frame comprising readily attachable and adjustable means for applying traction to a broken limb during knitting thereof and when it is supported in desired position by the frame.

Other objects, features and advantages of my invention will be apparent from the following description and the drawing wherein a preferred embodiment of my invention is clearly shown and described.

In the drawing, the single figure is a perspective view of a preferred embodiment of my invention.

Having particular reference to the drawing, a bed is generally indicated at 1 by dotted lines and has a head 2, foot 3, and side rails such as 4. An upright support post 5 comprises longitudinally adjustable and telescopically engaging tubular parts 6 and 7 with the tubular part 7 secured at one end to a saddle 8 by a flanged coupling 9; the flanged coupling 9 preferably being secured to the saddle 8 by rivets such as 10. The tubular part 6 is split at one end, as at 11, and is provided with ears 12 adjacent the split. A wing screw 13 extends through one of the ears 12 and is threaded into the other ear to clamp the tubular part 6 in a fixed position with respect to the tubular part 7. The saddle 8 is secured to the head 2 of the bed by clamps comprising substantially U-shaped members 14 and 15, co-operating cross pieces 16 and 17, and thumb nuts, such as 18 and 19, that are threaded onto the sides of the U-shaped members.

Another upright support post 20 preferably comprises a substantially rectangular tubular member 21 having integral flanges 22 at one end that are secured to a saddle 23 by rivets or other suitable fastening means 24. The saddle 23 is secured to the foot 3 of the bed by clamps which comprise substantially U-shaped members 25 and 26, co-operating cross pieces 27 and 28, and thumb nuts, such as 29 and 30, that are threaded onto the sides of the substantially U-shaped members 25 and 26.

Pads of felt 31 and 32, or other suitable material, are preferably placed under the clamps and saddles 8 and 23, respectively, adjacent the bed to prevent marring of the bed.

A bar 33 extends between the tops of the upright support posts 5 and 20. The bar 33 is pref-

erably tubular and preferably has a substantially rectangular or polygonal cross section. Flanges such as 34 on the upper end of the support post 5, and 35 on the upper end of the support post 20 provide seats for the bar 33 and are preferably so disposed that the vertical axes of the support posts 5 and 20 are substantially diagonal to the section of the bar. The flanges, such as 34 and 35 on the support posts 5 and 20, have slots, such as 36 and 37, respectively, at the ends thereof which engage thumb screws, such as 38 and 39, that are threaded into caps 40 and 41 which secure the bar 33 in place with respect to the support posts 5 and 20. The slots, such as 36 and 37 in the ends of the flanges 34 and 35, are provided to make removal of the caps 40 and 41 both quick and easy. The caps 40 and 41 are preferably angular and fit the surface of the bar 33.

Arms 42, 43, and 44 extend outwardly from the bar 33 and are supported thereby substantially at right angles to the bar and parallel to the surface of the bed. The arms 42, 43, and 44 are secured to the bar 33 by flanged couplings 45, 46, and 47, co-operating caps 48, 49, and 50, and thumb screws 51, 52, and 53, respectively. The flanged couplings 45, 46, and 47 and their co-operating caps 48, 49, and 50, respectively, have flat surfaces engaging the bar 33 to prevent rotation of the arms 42, 43, and 44, with respect to the bar 33. Pulleys 54, 55, and 56 are secured to the arms 42, 43, and 44, respectively, by clamps 57, 58, and 59; the clamps 57, 58, and 59 being adjustable longitudinally of the arms. The positions of the arms 42, 43, and 44 are adjustable longitudinally of the bar 33. An arm 60 is supported on the post 20 by a flanged coupling 61, co-operating cap 62, and thumb screws, such as 63. The arm 60 is adjustable longitudinally of the post 20 and prevented from rotation with respect to the post by engagement of the coupling 61 and cap 62 with the flat surfaces of the post. A pulley 64 is supported from the arm 60 by a clamp 65, which is adjustable longitudinally of the arm 60. A depending arm 66 is secured to and supported by the arm 42 by a coupling 67. A pulley 68 is secured to the depending arm 66 by a clamp 69 and is adjustable longitudinally of the arm 66. A depending hand grip 70 is supported from the bar 33 by a chain 71 and a clamp 72 to which the chain is secured and which is clamped around the bar 33.

An arm 73, which preferably comprises a rectangular bar, is secured to the post 20 by a clamp comprising flanges 74 on the end of the arm 73,

which engage the surface of the post, a cap 75, and co-operating thumb screws 76 which extend through the cap 75 and are threaded into the flanges 74. The arm 73 is substantially perpendicular to the post 20 and parallel to the foot 3 of the bed. Pulley support bars 77 are secured to and supported by a sleeve 78 that is slidably fitted onto the arm 73. The pulley support bars 77 have substantially parallel depending portions 79 and curved top portions 80 which space the parallel portions 79 from the foot 3 of the bed. Substantially parallel tubular members 81 are slidably mounted on the parallel depending portions 79 of the pulley support bars 77 and are secured in a desired position with respect to the pulley support bars by wing screws 82.

The tubular members 81 are connected by a U-shaped strap 83 intermediate the parallel portions 79 of the pulley support bars 77. The strap 83 provides bearings in which pulleys 84 and 85 are rotatably supported. A foot 86, having a tubular part 87 slidably mounted on the arm 73 and a saddle 88 resting against a pad 89 on the foot 3 of the bed, provides an auxiliary support for the arm 73. Thumb screw 90, threaded into the tubular part 87, secures the foot in a desired longitudinal position on the bar 73.

In the structure disclosed, the arms 42, 43, 44, 60 and 66 provide adjustable pulley supports which are utilized securely to support a patient's limb in a particular desired position. The pulleys 84 and 85 are utilized for suspending weights from a limb to provide traction on the limb.

By utilizing a rectangular central bar such as 33 of sufficient strength and rigidity between the support posts 5 and 20, the arms 42, 43, and 44 are firmly and nonrotatably supported in fixed positions with respect to the bar 33 without the

necessity of a double support frame or other auxiliary supporting structure. The elimination of the additional supporting frame or auxiliary supporting structure provides better access to the patient and bed and simplifies the structure. Also the diagonal relation between the cross section of the bar 33 and the axes of the support posts 5 and 20 provides greater rigidity in the direction of maximum stress. The adjustment of the length of the support post 5 by longitudinal movement of the part 6 with respect to the part 7 is utilized to level the bar 33 with respect to beds having different heights of heads.

While I have illustrated and described a preferred embodiment of my invention, many modifications may be made without departing from the spirit of the invention and I do not wish to be limited to the precise details set forth but desire to avail myself of all changes within the scope of the appended claim.

I claim:

In a surgical frame for hospital beds, in combination, comprising an end support post adapted to be secured to an end of the bed, the support post having a plurality of angularly disposed sides, means for securing the support post to the end of the bed, an arm extending from the support post and also having a plurality of angularly disposed sides, clamping means for the arm engaging the sides of the support post to secure the arm in position and prevent rotation of the arm with respect to the support post, a pulley support having a tubular part fitted to the arm and adjustable longitudinally of the arm, and a foot having a tubular part fitted to the arm and means engaging the bed to brace the arm.

EARL E. LONGFELLOW.
